US00D739021S

(12) United States Design Patent
Christensen et al.

(10) Patent No.: US D739,021 S
(45) Date of Patent:  Sep. 15, 2015

(54) OPHTHALMIC STRUCTURE(71) Applicant: OASIS Medical, Inc., Glendora, CA (US)(72) Inventors: James Marlow Christensen, Glendora, CA (US); D. Michael Colvard, Encino, CA (US)(73) Assignee: OASIS MEDICAL, INC., Glendora, CA (US)() Term: 14 Years(21) Appl. No.: 29/457,130(22) Filed: Jun. 7, 2013
